UNITED STATES PATENT OFFICE.

ELIHU THOMSON, OF SWAMPSCOTT, MASSACHUSETTS, ASSIGNOR TO THE
GENERAL ELECTRIC COMPANY, OF NEW YORK.

SYSTEM OF ELECTRICAL DISTRIBUTION.

SPECIFICATION forming part of Letters Patent No. 625,816, dated May 30, 1899.

Application filed September 10, 1897. Serial No. 651,212. (No model.)

To all whom it may concern:

Be it known that I, ELIHU THOMSON, a citizen of the United States, residing at Swampscott, in the county of Essex, State of Massachusetts, have invented certain new and useful Improvements in Systems of Electrical Distribution, (Case No. 616,) of which the following is a specification.

The present invention relates to the regulation of an electric current in systems of distribution in which constant-potential alternating currents are employed with translating devices requiring constant current.

It has for its object to preserve in a large degree the advantages attendant upon both systems and to overcome some of the defects of each. For example, it permits me to employ the small conductors suitable for high-tension currents, with consequent saving in copper. At the same time the difference of potential between the mains or between the line and ground is approximated to that of the constant-potential system. By a suitable application of the principles of this invention the difference of potential referred to may, indeed, be reduced to any desired degree, limited only by consideration of economy. I also combine the regulation of the two systems in such manner that although the source of current may be one designed for constant-potential the effect in the regulated circuit is that of constant current.

The accompanying drawings are diagrams illustrating the principles of my invention. Figure 1 is one form, and Fig. 2 a modification.

In Fig. 1, $l' l^2$ represent the sides of the constant-potential alternating-current system, feeding any kind of translating devices. A branch starting at a passes through the secondary S of a transformer T' , which is of the constant-current type, the primary P of which is connected in shunt to the mains $l' l^2$. In circuit with the secondary S is a series of translating devices, such as lamps L , which may be followed by a coil S^2 , a second set or series of translating devices L' , &c. This constitutes a series system, with a distribution of lights and secondary coils of transformers in series. Taken from the mains $l' l^2$ at some convenient point are submains $b^3 b^4$,

from which may be again branched wires b^5 b^6 , feeding a primary coil P^6 , of which S^6 is the secondary in a transformer. Suitable fuses $F F$ are provided in the branch wires wherever necessary. In like manner branches feed P^5 , the secondary corresponding to which is S^5 in the transformer shown, and P^4 corresponds in the same manner to S^4 . The transformers $P^6 S^6$ to $P^2 S^2$ may be of constant-potential type.

The action of the system is as follows: It may be desired to work a large number of lamps in series. The potential of the system $l' l^2$ may be adapted to take care of such a load; but at the same time it may be desirable to so divide up the potential as not to have it at any point in the system so high as would be required to work all the lamps in series. In this case the primaries $P^2 P^3$, &c., being supplied by the constant-potential lines $l' l^2$, set up currents at any desired ratio of transformation of potential in $S^2 S^3$, &c., which, being in the same direction as the impressed potential from the lines $l' l^2$, give, as it were, a "tandem" generation of potentials, with the load between these generators or secondaries S^2 to S^6 . The total effective potential is thus very much increased on the system over what it would be if the potential on the lines $l' l^2$ were alone impressed on the series system. At the same time at no point in the system or the load can there be any greater potential difference between line and earth or between the two lines than the highest potential of any secondary S^2 , &c., or the potential of the lines $l' l^2$.

The regulation of the current to constancy in such a system where minor variations of load occur is readily accomplished by the transformer T' , with its primary and secondary related as in a constant-current transformer of any approved type, where an increase of current traversing the secondary would be beaten down and kept constant or a decrease provided for by the opposite effect. I have shown a core C with an air-gap in the magnetic circuit as one well-known form of such a transformer, for which any equivalent acting device may be employed. By connecting an electrostatic voltmeter E across the terminals of the coil S or P of the transformer

T' the exact amount of work done by the coil S may be followed and the condition of the load in relation to the impressed potentials noted. Should it be desired to cut out any 5 set of lamps, as L, without disturbing the action of the system, this can be done by short-circuiting both the secondary S² and the lamps L by a suitable switch V, which switch is constructed to open at the same time the branch 10 circuit through the coil P² or the primary corresponding to the shunted secondary S². This leaves the system in balance, as before, with a portion of the load cut out.

If it be desired to operate the system independent of any direct connection—such as a 15 b, taken from the mains l' l²—the connections a b would be severed and connected across, as shown by the dotted line. In such case there would of course be a diminution in the 20 load carried, since the effective potential is decreased by an amount equal to the difference of potential between l' l²; but the system so far as the coils S² to S⁶ or their corresponding 25 primaries are concerned would remain the same. The advantage of a division of the feeding potential and the load would be maintained, so that in spite of the fact that the total effective potential on the connected system of secondaries and lights might be very 30 high there would be at no point a greater potential difference between parts of the line or ground than the total potential of any one secondary. In such a system the regulating 35 relation of the constant-current transformer T' and the coils P S would remain the same as before.

The system permits of other modifications which are exhibited in Fig. 2. The feature of the system just described, which consists 40 in the employment of a single constant-current transformer to bring the current to constancy and regulate for variations from constancy in the system, but which is not in itself a constant-current system so far as the 45 action of other devices are concerned, is employed in a different way in this figure; but in this instance there is no such advantage attained as the one which results from the connection of the electromotive-force sources 50 in series with the portions of the load, whereby a very high potential system becomes safe on account of the subdivision of the potential. In Fig. 2 the mains l' l² are branched at a b through a series of primary coils P² to P⁷, 55 which may be of the constant-potential type. This line is carried through the secondary of a constant-current transformer T', the primary of which is represented at P. This transformer T' has a wide range and tends to prevent 60 any departure from constancy of the other coils with which it is in series. The primaries P², &c., have corresponding secondaries S² to S⁷, the potentials in which may be greater or less than that between the terminals of any 65 primary. The load upon these secondaries would be a certain number of translating devices in series generally or a certain number in

multiple arc, as with secondary S⁷. If the potential around any primary P² with a constant current flowing were, say, three hundred volts, 70 the winding may be such as to cause the potential around S² corresponding to it to be one thousand volts or less and the number of lamps L worked by such secondary S² would correspond to a number consuming one thousand volts. Any other ratio might exist in the other coils, provided the work of each is proportioned properly, or they may all be of standard potential in the system. The cutting out of a coil P² by shunting can be effected 80 with the extinguishing of the lights corresponding to it, as those at L, while the constant-current transformer T' makes up the difference and keeps the current constant for the rest of the circuit, notwithstanding the 85 constant potential between l' l².

An accidental opening of the circuit of the line L with its lights would cause a very high potential at the terminals of S² or P² and interfere with the effectiveness of the system; 90 but this can be provided for readily by placing a film cut-out to be punctured by this high potential, which film cut-out may span the terminals of the secondary S², or, as in the case of the coil P³, it may span the terminals of the coil P³, as at F. In case of rupture of the corresponding secondary circuit the film cut-out will be punctured if properly proportioned and shunt the system, thus permitting the working of the remaining load, 100 which would be regulated as to its normal operation by the constant-current transformer.

What I claim as new, and desire to secure by Letters Patent of the United States, is—

1. In a system of distribution, the combination with constant-potential mains, of a circuit across them containing constant-potential transformer-windings connected in series, and a regulator in the series for maintaining the current therein constant. 110

2. In a system of distribution, the combination with constant-potential mains, of constant-potential transformer-windings connected in series across the mains, and a constant-current secondary connected in the series circuit. 115

3. In a system of distribution, the combination with constant-potential mains, of a circuit across the mains containing a number of transformer-secondaries of the constant-potential type connected in series, with translating devices between them, and a regulating device connected in the series circuit and tending to maintain constant current therein. 120

4. In a system of distribution, the combination with constant-potential mains, of a circuit across said mains containing transformer-windings normally supplying energy to translating devices in series therewith, and means for maintaining a constant current in said circuit. 125

5. In a system of distribution, a circuit containing a plurality of translating devices normally supplied with energy from a plurality

of transformer-windings in series and means for maintaining a constant current in said circuit.

6. In a system of distribution the combination of groups of translating devices and secondary windings alternately connected in series, and a primary circuit for supplying energy to all of said secondary windings.

7. In a system of distribution, the combination of translating devices in series, transformer-secondaries in series with each other and with said devices and normally supplying energy thereto and means for supplying energy to said secondaries.

15 8. In a system of distribution, the combination of translating devices, transformers of the constant-current and of the constant-potential type having their secondaries in series with said translating devices, and means for supplying energy to said transformers.

9. In a system of distribution, the combination of secondary windings in series, a primary circuit supplying energy for all of said secondary windings and translating devices

25 arranged in series and interposed between said secondary windings.

10. In a system of distribution, the combination of secondary windings in series, a primary circuit supplying energy for said secondary windings, translating devices in the circuit between said windings but not in shunt to one of the windings, and means for regulating the amount of energy consumed by said translating devices.

35 11. In a system of distribution, the combination of a plurality of transformer-secondaries connected in series across constant-potential mains and means for maintaining a constant current in the circuit including said

40 secondaries.

12. In a system of distribution, the combination of secondary windings in series, a primary circuit supplying energy for said sec-

ondary windings, translating devices in the circuit between said windings and means for 45 simultaneously cutting out of circuit a secondary winding and translating devices.

13. In a system of distribution, a circuit containing translating devices in series with a plurality of sources of electromotive force 50 and means for simultaneously eliminating translating devices and one or more of said sources of electromotive force from the circuit.

14. In a system of distribution, the combination with constant-potential mains, of constant-potential transformers having their secondaries connected in series, with translating devices connected in series between them and requiring approximately constant current for 60 their proper operation, the primaries of the constant-potential transformers being in shunt across the mains, and a constant-current transformer the secondary of which is connected in series with the other secondaries 65 and the translating devices, and the primary of which is connected across the mains.

15. In a system of distribution, the combination of a plurality of transformers with their secondaries connected in series with 70 each other and with a plurality of translating devices to which energy is normally supplied through the medium of said transformers, and means external to said transformers for regulating the current in said secondaries. 75

16. The combination with a series system of translating devices of a plurality of transformer-secondaries arranged in series therein and all of said secondaries normally furnishing energy thereto.

In witness whereof I have hereunto set my hand this 4th day of September, 1897.

ELIHU THOMSON.
